UNITED STATES PATENT OFFICE.

DAVID L. DOERING, OF KANSAS CITY, MISSOURI.

EXPLOSIVE-ENGINE.

SPECIFICATION forming part of Letters Patent No. 761,363, dated May 31, 1904.

Application filed December 15, 1902. Serial No. 135,257. (No model.)

To all whom it may concern:

Be it known that I, DAVID L. DOERING, a citizen of the United States, residing at Kansas City, in the county of Jackson and State 5 of Missouri, have invented certain new and useful Improvements in Explosive-Engines; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My present invention relates to engines, and has for its object to provide mechanism adapted to greatly reduce the resistance in engines, whether they are operated by steam or other power.

20 Further objects of my invention are to provide many improved details of structure. In the following specification and accompanying drawings I have described and shown my invention as the same is when attached to rotary engines and when gas or gasoline is used 25 as a motive power.

In the drawings, Figure 1 is a side elevation of my engine complete. Fig. 2 is a front end view of the same. Fig. 3 is a rear end 30 view of the same. Fig. 4 is a longitudinal sectional view of the compression-cylinder. Fig. 5 is a cross-section through the compression and engine cylinders. Fig. 6 is a longitudinal section through the engine-cylinder and piston. Fig. 7 is a cross-section 35 through the pump-head and the compression-cylinder head, showing the connection between the two parts; and Fig. 8 is a detail sectional view showing the inclined ways at 40 the end of the abutment.

Referring to the drawings in detail, 1 is the bed-plate, and 2 designates the standards supporting a rotary or other engine 3, which may be of any suitable type, but is preferably 45 of the type herein shown and described. Such engine is provided with a cylindrical casing, on the inner side of which is secured an inclined abutment 4, extending between the exhaust-passage 5 and the passage 6 between 50 the compression-cylinder and the en-

gine-cylinder. The piston 7 of the engine is cylindrical, having an annular groove adapted to receive the abutment 4, and is keyed to the shaft 8.

9 represents packing-bands set in annular 55 grooves in the flanges of the piston 7 and secured against rotation with the piston 7 by bolts 10, seated in the casing of the engine. The piston 7 is provided with one or more recesses 11. (One only shown in drawings, see 60 Fig. 6.) The recess 11 is adapted to receive a piston-head or paddle 12, maintained in projected position by coil-spring 13, seated in the bottom of the recess 11 against shaft 8.

Shaft 8 is provided with a central passage 65 or duct 14, extending therethrough to a point immediately beneath the recess 11, into which the same is tapped. At the end of the abutment 4, near the passage 6, are a pair of inclined blocks or projections 15, spaced apart 70 and arranged on edge and forming ways for the descent of the piston-head 12. At its outer end the shaft 8 is suitably journaled at the top of one of the standards 2 and is provided with a bevel-wheel 16, keyed thereto 75 and engaging a second bevel-wheel 17, keyed to the shaft 18, journaled on standard 19. Shaft 18 is provided at its opposite end with a suitable eccentric gear 20, connecting it with the piston-rod 21 of the pump 22, mounted on the top of the compression-cylinder, to be hereinafter described.

The piston-rod 21 is provided at its inner end with a piston 23, which reciprocates within the casing of the pump 22. The head 24 of 85 the pump 22 has bolted thereto on top a valve-housing 25, containing any suitable form of valve, (preferably a plug-valve,) and the said housing 25 communicates with the pump-head 24 through perforation 26 therein.

27 is a supply-pipe leading to any suitable carbureter. (Not shown.) The pipe 27 is coupled to the housing 25. The valve in the housing 25 has a stem 28 pivotally connected to the link-bar 29, pivotally connected to an 95 upright arm 30, slidably mounted on the piston-rod 21 and held normally projected by a spring 31 on said piston-rod 21.

32 is a collar rigidly secured to piston-rod 21 and adapted to force arm 30 inwardly in 100

opposition to spring 31 upon the inward stroke of the piston-rod 21. In the outward-projected position of the arm 30 the valve-stem 28 is in a position holding the valve in the 5 housing 25 open.

The compression-cylinder 33 has in its head an elbow-duct 34, connecting the interior of the pump-head 24 with the interior of the compression-chamber 35. Closing duct 34 at its lower end is a spring-controlled valve 36, opening into the chamber 35 and having its stem 37 extending transversely through the duct 34 and the head of the compression-cylinder and 10 through a suitable stuffing-box 38 exterior to the cylinder. Between the stuffing-box 38 and the outer end of the stem 37 is mounted on the said stem a spring 39, controlling valve 36.

20 40 is a sparker of usual structure located within chamber 35 and having two contact-points normally out of contact. One of the contact-points of the sparker 40 is capable of oscillation and passes through a suitable stuffing-box on the exterior of the cylinder 33 and has at its outer end a spring-pressed arm 41. At the top of the pump-head 24 is a bell-crank 42, fulcrumed at 43. Connecting the bell-crank 42 and the arm 41 of the sparker 25 40 is a link-bar 44.

45 is a spring controlling arm 41 and serving to maintain the engaging arm of the bell-crank 42 in perpendicular position.

The link-bar 29 projecting beyond the point 35 where the valve-stem 28 is pivoted thereto, upon the inward stroke of the piston-rod 21 the end 46 of the link-bar 29 depresses upon engagement the bell-crank 42, bringing the contact-points of the sparker 40 together.

40 Centrally located within the compression-cylinder 33 and forward of the passage 6 therein is a valve-seat 47, seating the valve 48, having a rear concave face 49 and carried by a valve-stem 50, passing through the rear 45 end of the cylinder 33. The stem 50 carries a spring 51 thereon between the valve 48 and the rear end of the cylinder 33. The stem 50 passes through a suitable stuffing-box 52 at the end of the cylinder, and its outer end is 50 slidably journaled in a frame 53, bolted to the end of the cylinder 33. Between the stuffing-box 52 and the frame 53 is positioned a spiral spring 54, the tension of which may be regulated through the adjustment of a collar 55 on the stem 50.

55 56 is a pump having a suitable water-supply pipe 57 tapped into the same and also a suitable exhaust-pipe 58 connecting the same with the duct or passage in the shaft 8. The 60 pump 56 is operated by eccentric gear 59, located on shaft 18 between bevel-wheel 17 and standard 19.

The operation of my improved engine is as follows: Upon the outward stroke of the piston-rod 21 the spring 31 forces the arm 30 out-

ward, opening the valve in the housing 25 and allowing the piston 23 to draw carbureted air and gasoline or other suitable mixture through pipe 27 into pump-head 24, suction through duct 34 being prevented by valve 36, 70 which is normally closed. Upon the inward stroke of the piston 23 the valve in housing 25 is closed, and the mixture which has been drawn into the pump-head 24 is forced through duct 34, overcoming valve 36 and passing 75 into chamber 35. At the same time sparker 40 is operated through contact of friction-wheel 46 on the link-bar 29 with bell-crank 42, thereby exploding the charge within chamber 35. The pressure from the exploded gases 80 overcomes valve 48 and escapes through passage 6 into the engine-casing, striking paddle 12 and forcing same over inclined abutment 4, the spring 13 giving way and allowing the depression of the paddle 12. At the end of 85 the abutment the paddle 12 descends over the ways 15, which are spaced apart to permit the pressure to find its way to the rear of the paddle, and thereby prevent the same from being forced back against the abutment, which 90 would result in stopping the engine. The pump 56 supplies a continual stream of water through duct 14, which escapes through recess 11 and exhaust-port 5 and acts to keep the parts 95 of the engine in cooled condition.

The spring 54 may be tensioned to any strength to resist any degree of pressure within the chamber 35. The spring 51 and the concave face of the valve 48 create sufficient resistance to the valve to prevent injury to the same upon its action.

When steam is employed in my engine, the pump 22, the sparker 40, and the valve controlling the pipe 27 are dispensed with, and, the pipe 27 being connected up to a suitable steam-boiler at one end and being connected at its other end to the duct 34, upon the steam within the chamber 35 reaching a suitable pressure valve 48 is overcome and the steam escapes into the engine-casing, striking the piston-head or paddle 12 with results hereinbefore described.

I do not desire to be understood as limiting myself to the employment of a rotary engine in the use of my invention, inasmuch as the same may be attached to an ordinary reciprocating-piston engine or an engine of any other common type.

Having thus described my invention, the following is what I claim as new therein and desire to secure by Letters Patent:

In an attachment for engines, the combination with the compression-cylinder having an outlet-passage intermediate its ends, an explosive-chamber portion in front of the outlet, an air-cushion portion in the rear of the outlet, forming a continuation of and of the same width as the explosive-chamber and an annular valve-seat between the explosive-chamber portion and the outlet reducing the 130

diameter of the rear end of the explosive-chamber, of a valve normally covering the outlet having its front reduced and normally resting in the reduced portion of the explosive-chamber and seated upon the annular seat, and its rear face concaved and exposed to and of a diameter approximately equal to the air-cushion portion of the compression-cylinder, a valve-stem extending from the rear face of the valve through an opening in the head of the

air-cushion portion of the cylinder, and means for regulating the pressure of the valve upon its seat.

In testimony whereof I affix my signature in presence of two witnesses.

DAVID L. DOERING.
